(57) **CLAIM**

The ornamental design for a multi-port valve, as shown and described.

DESCRIPTION

FIG. 1 is a front isometric view of a multi-port valve composed of a valve body and a directional.

FIG. 2 is a rear isometric view of the multi-port valve of FIG. 1.

FIG. 3 is a front elevation view of the multi-port valve of FIG. 1.

FIG. 4 is a rear elevation view of the multi-port valve of FIG. 1.

FIG. 5 is a right side elevation view of the multi-port valve of FIG. 1.

FIG. 6 is a left side elevation view of the multi-port valve of FIG. 1.

FIG. 7 is a top plan view of the multi-port valve of FIG. 1.

FIG. 8 is a bottom plan view of the multi-port valve of FIG. 1.

FIG. 9 is a front isometric view of the valve body of the multi-port valve of FIG. 1.

FIG. 10 is a rear isometric view of the valve body of FIG. 9.

FIG. 11 is a front elevation view of the valve body of FIG. 9.

FIG. 12 is a rear elevation view of the valve body of FIG. 9.

FIG. 13 is a right side elevation view of the valve body of FIG. 9.

FIG. 14 is a left side elevation view of the valve body of FIG. 9.

FIG. 15 is a top plan view of the valve body of FIG. 9; and, FIG. 16 is a bottom plan view of the valve body of FIG. 9. The broken line showing of unclaimed portions of the multi-port valve forms no part of the claimed design.

1 Claim, 12 Drawing Sheets
